Specification of Letters Patent. Patented Dec. 18, 1917.

Application filed January 13, 1916. Serial No. 71,865.

To all whom it may concern:

Be it known that I, LEWIS A. NICHOLS, a citizen of the United States, residing at Chicago, in the county of Cook and State of Illinois, have invented certain new and useful Improvements in Paper-Folders, of which the following is a specification, reference being had to the accompanying drawings, forming a part thereof.

The purpose of this invention is to provide an improved mechanism for the purpose of folding paper strips zigzag. It consists of the elements and features of construction shown and described as indicated in the claims.

In the drawings:

Figure 1 is a side elevation of a machine embodying this invention.

Fig. 2 is a plan view of the same.

Fig. 3 is a vertical longitudinal section at the line 3—3 on Fig. 2.

Fig. 4 is a vertical transverse section at the line 4—4 on Fig. 2.

Fig. 5 is a vertical longitudinal section at the line 5—5 on Fig. 2.

Fig. 6 is a detail section at the line 6—6 on Fig. 3.

Fig. 7 is a plan section taken as indicated at the line 7—7 on Fig. 1.

The machine illustrated in the drawings comprises main frame standards, 1, and 2, in which are mounted the shafts of the several paper-feed rolls and other devices extending across the entire width of the path 35 of the paper, and upon one of which are journaled the various wheels of the gear train for operating said rolls and other devices. It comprises also a shelf or table, 3, for holding the paper to be fed to the folding devices, which shelf is designed to be mounted either directly adjacent to the standards, 1, and 2, or at a distance therefrom when there is interposed between the said shelf and the standards, paper slitting 40 apparatus whose frame, 4, is in that case adapted to be connected to the standards, 1, and 2, and to have the shelf connected to its opposite end, as seen in Fig. 1.

The mechanism on the standards, 1, will 50 first be described. Mounted upon the standards, 1, 2, and extending rigidly from one to the other, there are two platens 5, 5, one above and the other below the path of the paper and having their proximate ends 55 spaced apart only sufficiently to afford a convenient free path for the paper between

them. Each platen has a rift, 5^a, extending through the platen from the end which faces the paper to the opposite end, and also extending through so much of the length of 60 the platen as covers the entire width of the paper to be creased and folded by the machine. Most conveniently the platens are produced with this rift by making them each of two blocks separated by spacers, 6, 65 6, near the ends and bound together rigidly, which is most conveniently effected by means of the bolts, 7, which bind the platens rigidly to the cross bars, 8, 8, which connect the two standards, 1, 2, of the main frame 70 of the machine.

In the rifts, 5^a, there are mounted for reciprocation toward and from the path of travel of the paper between the platens creaser blades, 9, 9, each made of a thin steel 75 plate and provided with a head by means of blocks, 10, 10, bolted on opposite sides of the steel plate at the end remote from the path of the paper. These heads are fitted between the opposite cross bars, 8, 8, for 80 sliding toward and from the platen; and springs, 10^b, are interposed between these heads and the platens respectively, reacting to hold the creaser blades withdrawn from the path of the paper. The edges of the 85 creaser blades toward the path of the paper are somewhat sharpened for creasing the paper, but dull enough to avoid cutting it when the creaser blades respectively are thrust across the path of the paper and 90 slightly into the rift of the opposite platens respectively. For operating the creasing blades to thrust them as described against the paper, there are journaled in the standards 1 and 2, at the upper end of the upper 95 platen and at the lower end of the lower platen, shafts, 11, 11, carrying rotating cam disks, 12, 12, each having a cam projection, 12^a, which in the rotation of the cam disk encounters a cam projection, 10^a, on the 100 proximate creaser heads, 10, and thrusts the creaser toward the path of the paper from which it is retracted by the springs, 10^b, when the cam projections, 12^a, pass by the cam projections, 10^a.

The train for operating the paper feed rolls and reciprocating the creasing blades comprises a pulley, 20, on a counter shaft, 21, driven by a belt, 22^a, from a pulley, 22, on the shaft of a motor, 23. A belt, 20^a, from a small pulley, 20^b, on the shaft, 21, 110 passes about a larger pulley, 24, fast on a

shaft, 24^a on which there is also fast a gear, 25, which by means of intermediate idler gears, 25^a, 25^b, drives a gear, 26, fast on the shaft, 26^b, of the paper feed roll, 27, which 5 coöperates with the pressure rolls, 60, hereinafter more particularly described for feeding the paper toward the platens. On the shaft, 24^a, there is rigidly mounted initial cone pulley, A¹, of a variable feed transmission device comprising with said initial cone pulley a companion cone pulley, A², and a belt, A³, which connects the two cone pulleys. The shaft, 30, of the cone pulley, A², carries rigidly a gear, 31, which by 10 means of intermediate idler gears, 31^a, 31^b, drives the gear, 33, fast on the lower one of the shafts, 11, and said gear, 33, by means of equal gears, 35, 35, meshing with and driving a companion gear, 33, on the upper 15 shaft, 11, rotates said two shafts, 11, 11, synchronously for causing them to reciprocate the creasing blades by means of the cam projections above described.

The paper to be creased and folded, 25 whether entering from the shelf, 3, or from the slitting apparatus, 4, is fed toward the platens by the feed rolls, 27, only when the coöperating pressure roll, 60, is let down upon the paper above said feeding rolls, and 30 the operation of this roll, 60, is controlled by means of abutments, 26^a, mounted on the side of the gear, 26, for rotation continuously by the shaft, 26^b, said abutments, 26^a, being positioned for encounter with the lever arm, 61^a, of the rock-shaft, 61, suitably journaled on the standards, 1 and 2, and carrying the roll, 60, by means of spring arms, 62, projecting from said rock shaft. The roll, 60, is pressed upon the paper by 40 the weight of the parts carried overhung from the rock-shaft, 61, as hereinafter described, but the spring arms, 62, permit slight inequalities to pass without transmitting movement to the rock shaft and the 45 overhung parts and thus insure smoother action than would be obtained with rigid arms. The roll, 60, is lifted from the paper as often in each revolution of the shaft, 26^b, as the abutments, 26^a, come around and 50 encounter the lever arm, 61^a, as above described. The abutments, 26^a, are held to the gear, 26, by bolts, 26^d, which can be tightened to hold them either in operative position for encountering the lever arms, 55 61^a, or out of such operative position, and one abutment only, or two oppositely situated abutments or all four of the abutments shown can be secured in operative position, so as to lift the roll, 60, once, twice or four 60 times in each revolution of the gear, 26. And any desired number of such abutments can be provided equally spaced on the side of the gear, 26, to lift the roll, 60, any desired number of times in each revolution of 65 the gear. During the time the roll, 60, is

lifted, the operator will push the paper sheet forward over the feed roll, 27, and against the gage, 65. The gage, 65, consists of a plurality of fingers mounted on a rod, 66, carried by slides, 66^a, guided in slide- 70 ways, 66^b, mounted on the frame standards and operated by a lever arm, 64, extended from the rock shaft, 61, and connected to the slides, 66^a, by links, 66^c. This connection causes the gage, 65, to be withdrawn from 75 the path of the paper when the pressure roll, 60, is lowered onto the feed rolls, and to be lifted into the path of the paper when the pressure roll, 60, is lifted from the feed roll. For the purpose of permitting accurate adjustment of the gage, 65, so that the ends of the gage fingers will withdraw below the path of the paper when the latter is engaged for feeding by the pressure roll, 60, descending onto the feed roll, the lever 80 arms, 64, are mounted loosely on the rock shaft, 61, and are adjusted thereabout relatively to the roll-carrying arms, 64, by providing them each with a two-part hub, 64^a, 64^b, the part, 64^a, having lugs, 64^c, between 90 which a finger, 64^d, of the hub member, 64^b, projects, adjusting screws, 64^e, 64^f, being set in opposite directions through lugs, 64^c, 64^c, which engage between them the finger, 64^d. The mode of adjustment by these screws will 95 be obvious. Inasmuch as the pressure roll, 60, is lowered onto the paper and the gage is depressed for clearing the path of the paper in a definite time in the operation of the train, these movements being caused by 100 the encounter of one of the abutments, 26^a, on the gear 26, with the lever arm, 61^a, of the rock shaft, 61, the movement of the paper is started from a definite point afforded by the position of the gage at 105 a definite time in the operation of the train which comprises the cams which operate the creasing blades, so that a definitely predetermined length of paper from the end is caused to pass by the creasing blades before the first of them is operated for creasing. 110

The foregoing description treats of only one feed roll, 27, and one pressure roll, 60, coöperating with the feed roll; but preferably and as illustrated, I mount on the shaft, 26^b, a plurality of feed rolls, 27, so that they or one or more of them may be adjusted to any desired positions on the shaft according to the width of the entire paper or of the 115 strips into which it is cut. These rolls or so many of them as may at any time be in service may protrude up through slots, in the table, onto which the paper is advanced by the operator from the shelf, 3, or by the 120 means provided from the shifting devices hereinafter described. Correspondingly, there are provided a plurality of pressure rolls, 60, which may be secured as described in positions on the shaft, 61, suitable for 125 130

bringing them in opposition to the feed rolls, 27, respectively.

In order to adapt the machine to handle various widths of quite narrow single strips there are provided in the table, 70, in the left hand part of its area slots, 70^a, quite closely placed,—through any one of which a feed roll, 27, may protrude to engage near the right hand margin, a strip whose width causes it to reach and lap the particular slot selected. Enough slots may be provided in the entire width of the table so that whatever be the width of the strips into which the sheet may be slitted, suitable slots may be selected for positioning under them on the shaft, 26^b, feed rolls which will engage respectively the several strips. The particular number shown is not to be understood as significant except as indicating any desired plurality.

The distance between the consecutive creases and folds of the paper will obviously be determined by the relation between the speeds of the feeding devices and the creasing blade operating devices, and for varying the distance between the creases, the variable speed transmission device, A, is provided between the trains which operate respectively the feed roll, 27, and the shafts, 11, by adjusting the transmission belt, A³, along the cone pulleys, A¹, and A². This speed relation may be changed as desired to any degree however small, and it is thereby rendered possible to make the paper folds of any desired width within the capacity of the machine.

When a wide sheet of paper is to be cut into strips, each of which is to be folded, the paper slitting apparatus, B, may be interposed between the shelf or table, 3, and ledge or chute board, 70, which leads to the feed roll, 27. This slitting apparatus comprises upper and lower parallel shafts, 80, 80, at the entering end, and similar upper and lower parallel shafts, 81, 81, at the discharge end, the shafts, 80, 80, having narrow belt pulleys, 80^a, distributed along their length at intervals corresponding to the width of the strips to be cut, disk cutters, 82, as illustrated, and preferably, also belt pulleys, 80^a, are provided on the shaft for each strip to be cut, that is, between each two consecutive cutters and outside of each of the extreme cutters, 82. The meeting plane of the belts, 84, 84, which pass around the belt wheels of the upper shafts and those which pass around the lower shafts is the plane of the table or shelf, 3, the papers each advanced from that table enter normally between the two contacting plies of the upper and lower belts and are lightly engaged thereby for feeding. To render the feed more effective, belt tighteners, 85, are provided consisting of pressure rolls indicated as carried upon the ends of lever

arms, 86, of rock shafts, 87, journaled so as to extend between the upper and lower plies of the two belts respectively, the tighteners operating upon the return or idle plies of the belts,—that is to say, the upper ply 70 of the upper belt and the lower ply of the lower belt. Further to increase the grip of the belt upon the paper to be fed, a pressure roller, 87^b, may be provided carried by lever arms, 87^a, of a rock shaft, 87^b, mounted between the two plies of the upper belt, said pressure roller bearing downward upon the inner or upper side of the lower ply of the upper belt, and pressing it toward the lower belt. It will be understood that the disk 80 cutters, 82, operate as rolling shears, the corresponding coöperating cutters upon the upper and lower shafts respectively having their proximate faces flat andlapping by each other as illustrated.

For controlling the paper movement after it passes by the feed roll, 27, to insure its proper position between the platens at the time of the operation of the creasing blades, feed rolls, 90, 90^a, are provided, one below 90 and the other above the path of the paper, just before it enters between the platens. The upper roll, 90^a, is preferably felt-faced for obtaining a softly yielding grip upon the paper, permitting it to slip when occasion requires, but feeding it with sufficient certainty to keep it smooth as it passes the creasing blades. For operating these rolls, 90, 90^a, there is provided upon the shaft of the lower one a gear, 91, which meshes with the gear, 26, the sizes of the gears, 91 and 26, relatively to the diameters of the feed rolls, 27 and 90, being such as to cause the two feed rolls, 27 and 90, to have the same circumferential speed. At the delivery side of the 105 platens, rolls, 92, 92^a, similar to the rolls, 90, 90^a, are similarly positioned, one below and the other above the path of the paper. The lower roll, 92, is driven from the roll, 90, by a gear, 91^b, meshing with the gear, 91, on the shaft of the roll, 90, and with an equal gear, 92^b, on the shaft of the roll, 92. The upper roll, 90^a, is carried in lever arms, 90^c, 90^d, extended from a shaft, 90^e, mounted in the end standards so that said roll, 90^a, 110 presses positively upon the paper traveling above the lower roll, 90. Somewhat similarly the upper roll, 92^a, is carried upon spring arms, 92^c, 92^d, extended from a fixed shaft, 92^e, similarly mounted in the end 115 standards. The pressure of the rolls, 90^a and 92^a, is adjusted as desired by setting the arms which carry said rolls on the shafts on which they are respectively mounted as indicated by the set screws, 90^f and 92^f, respectively. The spring arms which carry the roll, 92^a, cause the pressure exerted by that roll to be more yielding than that exerted by the roll, 90^a, as is desirable in order that the paper may yield slightly if necessary to 130

accommodate the creasing action. The rolls, 92, 92^a, guide and deliver the paper beyond the platens onto the ledge 94, which is positioned beyond said rolls, 92, 92^a, having 5 its upper surface in the plane of the carrying surfaces of the paper feeding devices, or substantially so.

It will be understood that the paper emerges beyond the rolls, 92, upon the ledge, 10, 94, having alternate creases for folding in opposite directions. In order that advantage may be taken of these creases for folding the paper and delivering it in a folded pile tucking devices are provided which will 15 now be described.

Perfectly similar mechanisms are mounted above and below the path of the paper. A description of either one will suffice for the other with slight exceptions which will be 20 indicated as the description proceeds. The upper devices will be first described, the description applying equally to the lower except as to statement of direction up and down to a certain point in the description 25 which will be indicated. At a convenient distance from the plane of the paper's path through the creasing devices, there are mounted in alinement with each other journaled in the opposite standards, 1 and 2, respectively short shafts, 100, extending transversely of the direction of travel of the paper parallel to the same, any convenient means being provided for rotating the shafts synchronously in fixed time relation to the 30 shaft, 11, which operates the creasing blades. In the construction as illustrated, the shafts, 11 and 100, rotate at the same speed, rotation for rotation. Fast on each of the shafts, 100, at its inner end is a cam disk, 102, which has 35 a crank pin, 107, at which there is connected a pitman, 108, whose end remote from the crank pin is guided in a vertical guide-way, 106, the end of the shaft, 105, hereinafter mentioned affording the engagement for such 40 guidance. The remote sliding ends of the pitman from the cam disks on each of the shafts, 100, are connected by a pivotally mounted tucker, 105, having as many tucker fingers or blades, 104, or sub-blades as the 45 maximum number of strips of creased paper at any time to issue from the creasing devices. Mounted on the main frame for reciprocating horizontally toward and from the vertical plane of the shaft, 100, and extending 50 across the path of thrust of the tucker blades on each of the standards at a position above and also at a position below the plane of the path of the paper more distant therefrom than half the length 55 of the plies in which the paper is to be folded, there are mounted spring-retracted slides, 108^a, the two slides at correspondingly opposite positions on the two standards being connected intermediate their ends 60 by a pivotally-rocking guide-bar, 109, which

is longitudinally slotted for the thrust therethrough of the tucker blade, 104. At 113 on each of the main frame standards, and about the level of the lower end of the guide-ways, 106, respectively, there are pivoted levers, 111, each carrying roll abutments, 111^a, for engagement by the periphery of the cam, 102, proximate thereto; the free ends of the levers being operatively connected by links, 112, with the proximate slides, 108^a, for pulling said slides against the yielding resistance of the retracting springs, 109^a, toward the bumper, 120, hereinafter described, against which the folded paper is to be accumulated. A stop pin set in any one of the pin-holes, 108^a, with which each of the slides, 108^a, is provided, serves to limit the retraction of the slide by the pin encountering the near guide-bearing, 108^b. Except as stopped in this way, the springs, 109^a, operate to hold the roll abutments, 111^a, against the peripheries of the respective cams, 102, 102. The cam disk, 102, comprises two concentric portions, 102^a and 102^b, differing in radius by the amount of the height of the cam shoulder or comparatively abrupt slope, 102^c, which connects said two concentric portions at one point in the circumference, said two concentric portions being connected at a point in the circumference substantially or approximately opposite the comparatively abrupt slope or shoulder, 102^c, by a more gradual slope, 102^d. These cams operate upon the lever link and slide systems, 111, 112, 109, to cause the tucker blades to oscillate back and forth between the delivery side of the creasing devices and the bumper in certain time relation to the thrust and retraction of the tucker blades derived from their connection with the crank pins, 107, on the cam disk. The roll abutment, 111^a, climbs the comparatively abrupt slope, 102^c, as the cam revolves, and runs down the gradual slope, 102^d, at a point about 180 degrees farther around in the revolution of the cam, and thereby the tuckers are given a comparatively abrupt swing toward the bumper and away from the delivery side of the creasing devices after the blades have been thrust respectively downward and upward and between the plies of the paper issuing from the creasing devices. The two tuckers, one thrust from above downward and the other thrust from below upward toward and into the path of the paper are thus oscillated back and forth toward and from the creasing devices in the intervals of their thrusting movement derived from the mechanism above described for folding the paper in accordance with the creases and accumulating it thus folded zig-zag in a compact pile against a bumper, 120. This is a board positioned vertically at a distance beyond the delivery side of the creasing devices and beyond the sweep of the tuckers, being lodged 136

at its lower edge upon a table, 121, upon which is slides, and extending from such table upward to an upper guide and check rail, 122, parallel with the table. Any convenient means may be provided for causing this bumper to yieldingly resist the pressure which packs the folded paper against it and to yield back upon proper pressure away from the creasing devices as the pile of zig-zag folded paper is accumulated against it on the side toward the creasing devices. As illustrated the only means shown for such yielding resistance is the inertia due to the weight of the bumper, and the friction of the same along its support; and usually this is quite sufficient to cause the paper to be compactly accumulated. Stops, 125 and 126, are provided upon the table, 121, and the top rail, 122, respectively, to limit the approach of this bumper to the creasing and tucking devices. These stops are preferably in the form of spring catches which have the further function of engaging the folds of the paper as they are pressed toward the bumper by the tuckers, and holding them while the tuckers withdraw and retreat for engaging the next fold. For this purpose they are attached respectively to the table and to the top bar.

The operation of the tucking devices may be understood from the foregoing description of the construction to be as follows:—

Assuming the parts of the mechanism in the position shown in Fig. 5, with the upper tucker at its extreme position inward, that is, toward the creasing mechanism, the upper creaser is about to be thrust down by the cam, 12, for making the next crease which will be in the direction for producing a downwardly-extending fold of the paper as it will be accumulated in the pile against the bumper, the last preceding crease having been made in the opposite direction and having resulted in the fold shown at *a*, the folded paper having been deflected upward upon its emergence from between the rolls, 92, 92^a, as shown by the lines indicating the position of the folded paper in Fig. 5. As the mechanism continues to operate from the position shown in this figure the roll abutment, 111^a, of the upper lever 111, will climb the abrupt slope or shoulder, 102^d, of the cam disk and withdraw the tucker guide and controlling bar, 108^a, abruptly away from the creasing mechanism, swinging the upper tucker, 104, toward the bumper and causing it to carry with it the fold of paper previously located behind it, that is, between it and the bumper,—pressing that ply of the paper upon the pile already accumulated against the bumper, thus completing the crease which was partially made by the creaser and causing the upper fold to pass the upper catch, 126, and become engaged behind it.

In the continued operation of the mechanism the rotation of the shaft, 100, by means of the crank and pitman connection causes the tuckers to be withdrawn upward and downward respectively from between the folds of the paper, such withdrawal being substantially direct,—that is, without swinging laterally toward or from the bumper while the concentric portions of the cams, 102, are rotating in contact with the abutments, 111^a, of the levers, 111, respectively. The two cams are relatively positioned so that the gradual slope, 102^d, of the lower cam reaches the abutment, 111^a, of the lower lever a little before the corresponding slope, 102^d, of the upper cam reaches a corresponding position with respect to the upper link, and the lower tucker is thereby swung over toward the creasing mechanism, carrying the upper end of the tucker past the lower fold of the paper a little before the similar operation of the upper cam causes the lower end of the upper tucker to be carried around the upper fold of the paper, and thereupon as the revolution of both the shafts, 100, continues, the lower tucker is thrust upward and the upper tucker thrust downward to engage respectively the next lower and the next upper fold of the paper.

It will be noted that the tuckers at the limit of their thrust toward the plane of the paper extend only slightly beyond that plane,—that is, the upper tucker extending slightly below it and the lower tucker slightly above it; and it will be understood that this adapts it to tuck the paper when it is folded in very short folds and to engage these short folds for compacting them against the bumper. It will be obvious that the table, 121, and the upper guide bar, 122, are necessarily mounted so as to be adjusted toward the plane of the paper according to the width of the folds being made,—that is, so that the table is below that plane and the guide bar above that plane a distance equal substantially to one-half the length of the paper plies or distance between the folds. Provision for such adjustment is made on the standards, 1 and 2, respectively, by clamping bolts, 128, set in selected holes of a vertical series of holes, 127, the bolts taking through slots, 128^a, in the brackets, 129, which carry the parts, 121 and 122, respectively, the length of said slots being as great as the distance between the holes, so that any desired position of the parts, 121 and 122, can be secured.

In folding tissue paper or any other light paper too flexible to be relied upon to stand upright upon its folds while being compacted against the bumper, and liable, on the contrary, to slump down on the table so as to defeat the proper piling of the paper as folded, it is desirable to provide means additional to or other than the tuckers for

gathering the paper as folded into compact pile. For this purpose there may be provided extending horizontally above and below the delivery rolls, 92, 92^a, respectively, tubes, 150, 150, having at their outer sides,—that is, the sides toward the bumper, a row of perforations, 150^a, for discharge of air against the paper folds as they are delivered and deflected respectively up and down from the plane of the paper. These tubes are connected with a source of compressed air so as to direct and discharge jets of air against the paper and against the several strips thereof when it is cut in strips at proper time to cause the folds to be held snugly against the tuckers respectively while the tuckers are swinging toward the bumper preventing the folds from sagging or slipping down while they are being packed or piled. To cause the air blast to strike the paper at the proper point to produce the result described, the apertures, 150^a, of the air pipes are positioned for directing the jets of air from the plane of emergence of the paper from between the feed rolls so as to intersect that plane a short distance beyond the ledge, 94, as seen in Fig. 5. This air blast may be advantageously employed with paper heavy or stiff enough to be piled by the tuckers alone and it may be employed to the exclusion of the tuckers when operating upon quite heavy or stiff paper.

For timing the air blasts to cause the effect above described the air is controlled by valves, 151^a, 151^a, in the pipes, 151, leading to the discharge tubes, 150, respectively, the valves being operated for opening in proper time with the tucker movements, by cams, 152, 152, on the shafts, which carry the cam disks, 102, respectively. It should be understood that although the foregoing description assumes a horizontal position of the paper as it passes through the creasing mechanism, and also assumes the folded product as accumulated against a vertical bumper, 120, this arrangement is not essential; for instance, the paper might be fed vertically downward through the creasing mechanism and accumulated upon a horizontally disposed bumper, 120, it being only necessary to provide a yielding support for said bumper to replace the frictional engagement with its table, 121, for insuring compact accumulation of the folded product. It is also feasible to feed the paper through the creasing mechanism in an oblique position downwardly toward an obliquely disposed bumper, and in some cases with such an arrangement a part of the wall, 122, may be omitted to provide an opening through which the folded product may be removed at intervals as desired.

I claim:

1. In a paper-folding machine, in combination with paper-slitting apparatus com-

prising cutting devices and paper-propelling devices which engage all the strips together after the paper has passed the cutting devices, paper-creasing devices positioned and extending across the width of all the strips and operating upon them all simultaneously and equally, and means beyond the creasing devices for delivering the creased paper in folded condition.

2. In a paper-folding machine, in combination with a paper-supporting table, paper-slitting devices to which the paper runs from the table, paper-feeding devices located beyond the slitting devices, paper-creasing devices located beyond the paper-feeding devices and extending across the width of all the strips, means for actuating said creasing devices to cause them to operate simultaneously upon all the strips, tucking devices located beyond the creasing devices, and means for actuating the tucking devices to cause them to operate simultaneously and equally upon all the strips.

3. In a paper-folding machine, in combination with paper-feeding means, two non-feeding platens independent of the feeding means in fixed position at opposite sides of the path of the paper, having rifts opposed to each other; creasing blades mounted in said platens respectively for thrust into the rifts of the opposite platen, and means for actuating said creasing blades for thrusting them alternately into said opposite rifts while the paper is being fed between the platens.

4. In a paper-folding machine, means for creasing the paper at transverse lines for folding alternately in opposite directions, said creasing means comprising rigid platens positioned at opposite sides of the path of the paper, spaced apart sufficiently to afford a free path for the paper between them; a creasing blade mounted in each of said platens for reciprocation across the path of the paper, springs which yieldingly resist the thrust of the blades toward said path and tend to retract and hold them out of the path; rotating cams operating upon said blades respectively for thrusting them toward the path of the paper at pre-determined intervals in the rotation of said cams, means for positively feeding the paper between the platens, and gear trains which operate said paper-feeding means and said rotating cams in pre-determined time relation to each other for creasing the paper at pre-determined intervals in its length.

5. In a paper-folding machine, creasing mechanism comprising means for feeding the paper longitudinally, adapted to actuate the same continuously at a pre-determined speed, rigid platens positioned at opposite sides of the path of the paper spaced apart sufficiently to afford a free path for the paper between them, each of said platens

- extending over the whole width of the paper; said platens having oppositely positioned rifts and creasing blades in said rifts respectively adapted each to be thrust into the 5 rift of the opposite platen, and means for actuating said creasing blades for so thrusting them alternately at pre-determined intervals while the paper is fed between the platens.
- 10 6. In a paper folding machine, in combination with paper-feeding rolls, two platens mounted upon opposite sides of the path of the paper traveling from the feeding rolls and spaced apart to afford a path for the 15 paper between them; creasing blades mounted in said platens respectively and extending through them in a direction transverse to the path of travel of the paper, heads mounted on said blades respectively, and 20 guide-ways for the heads formed on the platens for guiding the blades in thrusting movement toward the path of the paper, springs operating upon the heads for retracting the blades from the paper; cams 25 mounted for rotation at opposite ends of the platens respectively and operating upon said heads for thrusting them in toward the path of the paper, and means for rotating said cams timed with respect to the paper feed 30 mechanism and with respect to each other for alternately thrusting the creasing blades each into the rift of the opposite platen at pre-determined intervals in the travel of the paper.
- 35 7. In a paper-folding machine, in combination with paper-feeding rolls, paper-creasing blades whose sole movement for creasing is transverse to the direction of feed of the paper, a movement transmitting train in 40 which the rolls and blades are actuated respectively for feeding and creasing the paper, said train comprising speed-changing devices situated in the train intermediate the elements thereof which directly actuate 45 the feed rolls and the creasing blades; whereby the frequency of actuation of the blades with respect to the rate of feed of the paper above the rolls may be varied by the adjustment of the feed-changing devices.
- 50 8. In a paper-folding machine, in combination with paper-feeding rolls, non-feeding paper-creasing devices located along the path of the paper beyond the feeding rolls, and tucking devices located beyond 55 the creasing devices; a movement transmitting train in which the feed rolls, the creasing devices and the tucking devices are actuated, and change-speed devices in said train between the feeding rolls and the creasing 60 devices; the tucking devices being actuated in said train subsequent to the creasing devices; whereby the creasing and tucking devices are operated in unchanging time relation to each other, and in variable time relation to the paper-feeding devices.
9. In a paper-folding machine, in combination with means for feeding the paper and for creasing it alternately in opposite directions, tucking and piling devices comprising two tucking blades mounted at opposite 70 sides of the path of the paper beyond the creasing devices, two guides for each blade, one of said guides being fixed and the other movable in direction substantially parallel to the path of the paper; means for reciprocating the tucking blades in said guides, and means for reciprocating the movable guides transversely of the direction of reciprocation of said blades substantially at the limit of the said reciprocation of the blades. 75
10. In a paper-folding machine, in combination with means for feeding the paper and for creasing it alternately in opposite directions, tucking devices for folding the paper and piling it in accordance with the creasing, comprising two tuckers and two guides for the opposite ends respectively of each tucker for controlling its reciprocation transversely of the path of movement of the paper, the guide which is nearer the path of 80 the paper being mounted for reciprocation transversely to that of the tucker; a rotating shaft and connections therefrom for reciprocating the tuckers; a cam on said shaft, and connections by which the cam reciprocates the reciprocating guides. 85
11. In a paper-folding machine, in combination with means for feeding the paper and for creasing it alternately in opposite directions transversely of the path of feed, 100 means for folding it in accordance with the creasing, comprising two tuckers mounted at opposite sides of the path of the paper beyond the creasing devices for reciprocation across said path, guides for the remote 105 ends of said tuckers positioned and formed to control the movement of said remote ends substantially in a direction at right angles to the path of the paper, guides for the tuckers respectively intermediate said remote 110 ends and the operating ends mounted for reciprocation transversely of the direction of the reciprocation of the tuckers, springs operating upon said reciprocating guides 115 for retracting them in one direction; rotating cams; operating connections for the reciprocating guides operatively associated with the cams respectively; said cams having each an abrupt slope or shoulder for actuating the reciprocating guides abruptly 120 in the first mentioned direction, and means operating upon the remotely guided end of the tuckers for reciprocating said ends in said remote guides. 125
12. In combination with the paper feeding devices and devices constructed for creasing the paper for folding alternately in opposite directions, means positioned in the path of emergence of the paper from the creasing devices which impedes its advance 130

and causes it to start to fold in accordance with the creasing, a support beyond said impeding means extending transversely to the direction of emergence and advance of 5 the paper against which the folded paper may be accumulated, and air blast devices positioned for discharging air blasts toward said support from points beyond the paper and respectively at opposite sides of the 10 path of emergence; air pipes extending parallel to the plane of the paper's path at op-

posite sides thereof respectively, having discharge apertures positioned for directing air blasts toward said support from lines situated in a plane transverse to said path of 15 the paper and intersecting said path proximately to the emergence of the paper from the creasing devices.

In testimony whereof I have hereunto set my hand at Chicago, Illinois, this 11th day 20 of January, 1916.

LEWIS A. NICHOLS.
